HIGH PRESSURE BOILER INCLUDING A
WATER TUBE LINED FIRE BOX, PARTICULARLY FOR LOCOMOTIVES

Hans Nyffenegger, Winterthur, Switzerland, assignor to the firm Schweizerische Lokomotiv- und Maschinenfabrik, Winterthur, Switzerland

Application March 1, 1933, Serial No. 659,190
In Germany March 3, 1932

4 Claims. (Cl. 122—460)

This invention relates to high-pressure boilers including a water tube lined fire box, particularly for locomotives.

With high-pressure steam locomotives including a water tube fire box the construction and arrangement of the heating surface of the boiler to be combined with the fire box and the combustion chamber in a manner to satisfy all technical requirements as regards heat distribution, construction, and operation is a matter of considerable difficulties.

According to the present invention these difficulties are met in a boiler of the abovesaid type including a flue gas heated low pressure feed water preheater by disposing the superheater in a rearward flue gas chamber situated between the low pressure feed water preheater and the high pressure portion of the boiler and arranging a high-pressure feed water preheater in interengaging disposition with the smoke tubes of the low pressure feed water preheater.

In the accompanying drawing constructional forms of the invention are schematically exemplified, in which

25 Fig. 1 is a longitudinal section of the boiler.

Fig. 2 is a section on the line II—II in Fig. 1;

Fig. 3 is a section on the line III—III of Fig. 1;

Fig. 4 shows a modification of the low pressure feed water preheater.

30 Fig. 5 is a perspective view showing the manner in which the feed water preheater of Fig. 1 is connected up, and

Fig. 6 is a similar view as Fig. 5 for the modified feed water preheater of Fig. 4.

35 Referring to the drawing, the portion of the boiler for generating the high-pressure steam is shown to include, in a known manner, two upper steam collecting drums *a*, four lower water drums *b*, three sleeve stayed water filled plate walls *d* and

40 water tubes *c* which form the sides of the fire box and the combustion chamber and protect the upper drums from direct heating. *e* represents the grate. A flue gas heated low pressure feed water preheater *m* is secured for example by

45 a rigid screw connection *m*₁ to a chamber *f* situated in front of the high-pressure steam generating portion and screwed thereto also in a rigid manner (the other connection not being shown in the drawing). The chamber *f* accommodates

50 a spiral superheater *i*, and a flue gas chamber *g* comprises the customary blast nozzle appliance *h* for promoting the combustion. The chamber *f* is lined on the inner side of its shell with fire-proof material. The superheater *i* which is assumed to be a spiral superheater can be removed

in the upward direction through an opening in the chamber *f* normally closed by a cover *t*, a corresponding cover *t*₁ being provided in the shell of the boiler. Lateral doors *s* and *t*₂ in the chamber *f* and the boiler shell respectively provide access to the chamber *f*, when it is to be cleaned by blasting or in other manner. The rearward flue gas chamber *f* is provided with doors on all sides for giving access, when the chamber is to be cleaned by blasting or in other manner.

60 Discharge spouts *l* for cinders are arranged on the bottom of the chamber *f* and permit of removing the cinders that may collect thereat during the operation. Between the smoke tubes *n* of the low pressure feed water preheater the tube elements *o* of the high-pressure feed water preheater are inserted.

65 Admittedly, it is already known with the usual low pressure locomotive boilers including water tubes or smoke tubes respectively to pass the feed water through a feed water preheater arranged between the smoke or water tubes of the boiler prior to its entry into the boiler proper by means of a pump. These known arrangements are, however, fundamentally different

70 from the arrangement according to the invention in so far, as with the latter the feed water is forced into the high pressure feed water preheater after leaving the low pressure preheater, in the form of a smoke tube boiler, by means of

75 an intervening pump and connecting pipes *y*₁, *y*₂, and *y*₃, the high pressure being disposed between the smoke tubes of the low pressure preheater associated with the high pressure preheater. From the high pressure preheater the

80 water is passed to the upper steam collecting drums through pipes *y*₄, *y*₅. The pressure prevailing in the high pressure preheater is several times that of the low pressure preheater (for example 60 atmospheres as against 10 to 15

85 atmospheres of the latter) and thus also the feed water temperature attained in the high pressure preheater is 80 to 90 degrees C. higher than that of the low pressure preheater. The spiral tube elements *o* of the high pressure feed water preheater may be connected up in different ways. The entrance and exit headers *p* and *q* of the high pressure preheater are either both disposed in the chamber *g* (Figs. 1 and 5) or

90 separately arranged in the chambers *f* and *g* respectively (Figs. 4 and 6). With the latter arrangement a relative flow of the feed water and the flue gases similar to that provided by the counter course principle is obtained. The proportion of the heating surfaces of the low

95 100 105 110

and high pressure preheater is so chosen that in the low pressure preheater no low pressure steam at all is generated or else only an amount which is necessary for driving the feed pumps and auxiliary apparatus thereof. On the contrary, in the high pressure preheater the hot water withdrawn from the low pressure preheater by means of the pump is heated up to the temperature of saturation of the high pressure boiler and under certain circumstances even evaporated in small quantities. This desired effect is attained, when for example with a pressure in the high pressure boiler of 60 atmospheres and 15 atmospheres in the low pressure preheater the proportion of the heating surface of the high pressure preheater is approximately 1.3 to 1.5 times that of the low pressure preheater. Thus the low pressure feed water preheater serves merely for preheating the feed water and for separating out sludge. The feed of the low pressure preheater is effected in the usual manner by means of pumps or injectors (not shown).

The low pressure smoke tube preheater is equipped with a steam collector *s* for supplying the steam for driving the last-mentioned feed pumps or injectors, and with safety valves *r* and a water column *x*.

The relative arrangement of the heating surfaces and the mode of connecting up these surfaces provide a high efficiency for the boiler. At the same time sealing the passages for the flue gases and cleaning the same is considerably facilitated. The boiler according to the invention is of an extraordinarily simple construction and reliable in operation. As this result is obtained with the aid of known elements hitherto used to advantage in locomotive work, the boiler according to this invention is adapted for general application in connection with locomotives.

I do not limit myself to the particular size, shape, number or arrangement of parts as shown and described, all of which may be varied without going beyond the scope of my invention as shown, described and claimed.

What I claim is:

1. In a high pressure boiler of the type described particularly for locomotives in combination, a water tube lined fire box and combustion chamber comprising parts of a high pressure portion of the boiler and supplying substantially the whole steam energy consumed in the locomotive, a flue gas heated fire tube type low pressure feed water preheater generating at the most a slight percentage amount of low pressure steam energy, a flue gas chamber provided between said combustion chamber and said low pressure feed water preheater, a superheater for the steam generated in said lining of said fire box and said combustion chamber accommodated in said flue gas chamber, a high pressure feed water preheater interengaging with the fire tubes of said low pressure feed water preheater and receiving its water supply from said low pressure preheater, and a pump intercalated between said low pressure preheater and said high pressure preheater, for supplying the latter with water from the former.

2. In a high pressure boiler of the type described particularly for locomotives in combination, a water tube lined fire box and combustion

chamber comprising parts of a high pressure portion of the boiler and supplying substantially the whole steam energy consumed in the locomotive, a flue gas heated fire tube type low pressure feed water preheater generating at the most a slight percentage amount of low pressure steam energy, a flue gas chamber provided between said combustion chamber and said low pressure feed water preheater, a superheater for the steam generated in said lining of said fire box and said combustion chamber accommodated in said flue gas chamber, a high pressure feed water preheater interengaging with the fire tubes of said low pressure feed water preheater, the heating surface of the high pressure preheater being larger than that of the low pressure preheater, and a pump intercalated between said low pressure preheater and said high pressure preheater, for supplying the latter with water from the former.

3. In a high pressure boiler of the type described particularly for locomotives in combination, a water tube lined fire box and combustion chamber comprising parts of a high pressure portion of the boiler and supplying substantially the whole steam energy consumed in the locomotive, a flue gas heated fire tube type low pressure feed water preheater generating at the most a slight percentage amount of low pressure steam energy, a flue gas chamber provided between said combustion chamber and said low pressure feed water preheater, a spiral superheater for the steam generated in said lining of said fire box and said combustion chamber accommodated in said flue gas chamber, a high pressure feed water preheater interengaging with the fire tubes of said low pressure feed water preheater and receiving its water supply from said low pressure preheater, and a pump intercalated between said low pressure preheater and said high pressure preheater, for supplying the latter with water from the former.

4. In a high pressure boiler of the type described particularly for locomotives in combination, a water tube lined fire box and combustion chamber comprising parts of a high pressure portion of the boiler and supplying substantially the whole steam energy consumed in the locomotive, a flue gas heated fire tube type low pressure feed water preheater generating at the most a slight percentage amount of low pressure steam energy, a flue gas chamber provided between said combustion chamber and said low pressure feed water preheater and firmly connected to both of said parts, an upper wall in said chamber, a removable cover provided in said upper wall of said chamber, a spiral superheater for the steam generated in said lining of said fire box and said combustion chamber removably accommodated in said chamber and adapted to be passed out through an aperture normally closed by said cover, a high pressure feed water preheater interengaging with the fire tubes of said low pressure feed water preheater, the heating surface of the high pressure preheater being approximately 1.3 to 1.5 times larger than that of the low pressure preheater, and a pump intercalated between said low pressure preheater and said high pressure preheater, for supplying the latter with water from the former.

HANS NYFFENEGGER. 145
